Haber

UNITED STATES PATENT OFFICE

EUGEN HABER, OF BERLIN-CHARLOTTENBURG, GERMANY

AIR HEATER

Application filed June 14, 1926, Serial No. 116,060, and in Germany February 18, 1924.

It has become known to use, for the utilization of waste gases coming directly from furnaces at high degrees of heat, masonry heating ovens alone or in combination with 5 cast iron heaters connected behind said heating ovens.

In order to economize the considerable expenses for masonry heating ovens they are suppressed and metal heaters are used 10 exclusively for which, according to the invention, a new working method is applied.

The metal heaters used according to the invention are of the type described and shown in my prior Patent No. 1,635,838. 15 These heat exchanging bodies are composed each of a number of sheet metal plates the two heat exchanging media flowing along the two surfaces of each of these sheet metal plates in cross current so that alternating intersecting channels for the heat exchanging media are produced in the closed body, these bodies being adapted to be connected the one with the other by means of similar rectangular end-flanges to form 20 groups to be connected with tubular connections.

According to this method the heating gases are maintained, in a closed channel containing the heat exchanging elements, at 25 a continuous rolling flow by means of a fan, the admission of fresh heating gases taking place in the suction zone of this rolling flow and the discharging of the cooled gases in the pressure zone. The gas admission and 30 discharge is preferably effected centrally to the circulating flue so that the circulating gas quantity remains always constant even if an auxiliary cooling means is sucked in at the same time.

40 For carrying out this working method an air heating plant is used in which the open ends of the heating gas channels of the heat exchanging bodies which are arranged in pairs, are connected at both ends by connecting tubes in such a manner that a closed 45 circulating channel is formed, the short connecting tube serving to accommodate the blower, and the other tubular conduits for the gas admission and discharge in which 50 regulating means may be arranged.

The new plant is shown, by way of example, diagrammatically in the only figure of the accompanying drawing.

The heating plant consists of two heat 55 exchanging elements *a* *b* working at circulating current, or of two groups of such elements, through which the air to be heated or any other fluid flows in horizontal direction, preferably in the direction of the arrows *c*. The channels for the heating 60 gases or flue gases, for which steam might be substituted, extend perpendicular to the air channels and they are connected at the upper ends by a curved tube *d* in the wall of which a horizontal shaft *e* is journaled, 65 on which a fan *f* and on the outer free end of said shaft a driving pulley *g* are mounted.

To each of the bottom plates of the two 70 elements *a* and *b* a longer tube *h* is connected which, together with the elements *a* and *b* and the connecting tube *d*, form a closed 75 circulating channel. Into the tube *h* projects a pipe *i* having a central mouth *j* and designed for supplying the heating gases from any source of heat, for instance an 80 oven *k* or a heat accumulator the temperatures of said heating gases amounting to 800 to 1000° C. or more. The cooled heating 85 gases are discharged from the other arm of tube *h* through a pipe *m* having also a central mouth *n*. The two arms of tube *h* are narrowed at *o* above the open ends *j* and *n* of pipes *i* and *m* in order to obtain an ejector or suction pipe effect.

The pipes *i* and *m* comprise further 85 regulating elements *p*, as sliding dampers or the like, which are preferably positively connected the one with the other.

A supplying tube *r'* for a cooling medium, 90 as for instance air, is provided, which encloses the gas-pipe *i* and the end of said tube *r'* is central with regard to the mouth *j* or encloses a portion of pipe *i* like the tube *r*.

The operation of the plant is as follows: 95 As soon as the fan *f* has been started the contents of the circulating channel is moved so that a circulating current is produced. Fresh heating gases are sucked in at the same time from the supply pipe *i* whilst on 100

the pressure side a similar quantity of gases is discharged through the pipe *m* said gases having been utilized and cooled. The fresh heating gases, prior to coming into contact with the walls of the heat exchanging element *h* have been partly cooled by mixing with the existing circulating current so that the heating surfaces are protected against burning. The quantity of the gases may further be lowered, prior to entering into the elements, by sucking in of fresh air through the tube *r* or *r'*. The final temperature of the heated air, the air to be heated flowing transversal to the circulating current through the two elements *a* and *b* which communicate the one with the other, can thus be accurately regulated.

Instead of a fan *f* a centrifugal fan may be used which will be mounted directly upon the element *a*.

While the invention has been described as an invention for heating air by means of hot waste gases, the apparatus is also adapted to be employed for numerous purposes for which simple preliminary heaters for air or water are not adapted. The invention may be used as a condenser for steam turbines and engines, for an air cooler in a closed system for continuously circulating cooling air through generator windings of turbines, and as a recuperator for blast furnaces to pre-heat the air introduced through the tuyères by the hot waste gases. The apparatus, which can be cheaply manufactured, is adapted to replace costly fire brick structures now employed in recuperators.

I claim:—

1. An apparatus for heating air by means of hot waste gases, comprising in combination a pair of heat exchanging elements working in cross current and each having gas channels open at both ends and air channels, a short tube connecting the upper open ends of said heating gas channels, a long tube connecting the lower open ends of said gas channels of said two heating elements said short and long tubes forming together with the gas channels, a closed channel for a gas flow, a gas supply pipe connected to said long connecting tube, a gas discharging pipe connected to said long connecting tube opposite the point at which said gas supply pipe is connected, means for propelling the gas in the closed channel formed by said connecting tubes and by said gas channels in said heat exchanging elements, an air supply tube, and an air discharging tube connected to the corresponding ends of the air channels in said air heating elements.

2. An apparatus for heating air by means of hot waste gases, comprising in combination a pair of heat exchanging elements working in cross current and each having gas channels open at both ends and air chan-

nels, a short tube connecting the upper open ends of said gas channels, a fan mounted in said short connecting tube for accelerating the circulation of the gas in said closed gas channel, a long tube connecting the lower open ends of said heating gas channels of said two heating elements said short and long tubes forming together with the gas channels a closed channel for a gas flow, a gas supply pipe connected to said long connecting tube narrower than said long connecting tube and concentric to the same, a gas discharging pipe connected to said long connecting tube opposite the point at which said gas supply pipe is connected concentric to the same, and an air discharge tube connected to the corresponding ends of the air channels in said air heating elements, and regulating elements in said gas supply and discharging pipes.

3. In an apparatus for heating air as specified in claim 2 the arrangement that the long connecting tube has narrowed portions above the concentric gas supply and discharging pipes.

4. In an apparatus for heating air as specified in claim 2 in combination with the gas supply pipe, a supply pipe for fresh air arranged concentrically to said gas supply pipe.

5. In an apparatus for heating air by means of hot waste gases as specified in claim 2, the arrangement of a sliding damper in the discharging pipe for regulating the volume of the cooled gases discharged and the volume of the gases returned.

In testimony whereof I affix my signature.
EUGEN HABER.
